UNITED STATES PATENT OFFICE

HAROLD A. BURT, OF ST. ALBANS, NEW YORK, ASSIGNOR TO MERGENTHALER LINOTYPE COMPANY, A CORPORATION OF NEW YORK

TYPOGRAPHICAL MACHINE

Application filed October 1, 1930. Serial No. 485,581.

My invention relates to typographical machines, such as linotype machines of the general organization represented in Letters Patent of the United States No. 436,532, to O. Mergenthaler, wherein circulating matrices are released from a magazine in the order in which their characters are to appear in print and then assembled in line, the composed line transferred to the face of a mold, the 10 mold filled with molten metal to form a slug or linotype against the matrices which produce the type characters thereon, and the matrices thereafter elevated and returned through distributing mechanism to the magazine from which they started.

More particularly, it relates to that class of machines equipped with a plurality of magazines which are movably arranged so that any selected one thereof may be brought 20 into operative relation to the assembling and distributing devices; and its chief object is to provide an improved form of mechanism for effecting this movement of the magazines, as will be more fully described in the detailed description to follow, and finally 25 pointed out in the claims.

In the accompanying drawings, I have shown my invention in preferred form and by way of example, and as applied to a linotype machine, but obviously many changes 30 and variations may be made therein, and in its mode of application, which will still be comprised within its spirit. Thus, the details thereof may be widely varied and it 35 may be adapted to other forms of typographical machines, such as typesetters, type-casters and the like, which handle type or dies instead of matrices. Generally speaking, I desire it to be understood that I do not limit 40 myself to any specific form or embodiment, except in so far as such limitations are specified in the claims.

Referring to the drawings:

Fig. 1 is a side elevation of a portion of a 45 linotype machine having my invention applied thereto;

Fig. 2 is a similar view, on an enlarged scale, of the magazine shift frame and its 50 raising and lowering mechanism;

Fig. 3 is a detail view taken on the line 3—3 of Fig. 2;

Fig. 4 is a plan view of the parts shown in Fig. 2;

Fig. 5 is an enlarged cross section taken 55 on the line 5—5 of Fig. 2;

Fig. 6 is a view similar to Fig. 2, but showing the parts in an elevated position; and

Fig. 7 is a transverse vertical section taken 60 on the line 7—7 of Fig. 6.

The matrices X are stored according to font or otherwise in the magazines A, three of which are shown herein, but of which a greater or less number might be employed if desired. The several magazines are 65 removably mounted upon separate base frames B, as by means of lips or shoulders B¹ rising from the forward or lower ends of the base frames and engaging in front of cross ribs or plates A¹ attached to the undersides of 70 the magazines. The three base frames B are all connected, as by means of screws B², to a pair of side plates C,—these parts thus constituting a rigid shift frame for the magazines. The shift frame is in turn mounted 75 in a relatively fixed supporting frame D pivoted at its upper end, as at D¹, to the machine frame and resting loosely at its lower end upon adjusting screws D² carried by the machine frame.

It may here be stated that the magazines A are of rectangular shape and of the short variety, being intended for use as auxiliary magazines in machines of the commercial Model 14 type. For this reason, there is employed in connection with the magazines a channeled conductor E which serves to connect the active one thereof with the customary magazine entrance F leading from the distributing mechanism G. As will be noted 80 from Fig. 1, both the magazine entrance F and the channeled conductor E are mounted directly on the supporting frame D.

In the embodiment illustrated, the magazines are each provided with a fixed bank of escapements H which are adapted to be actuated by a common series of pivoted levers H¹ operated from the main keyboard (not shown) through rocking bails H², reeds H³, and small intermediate levers H⁴. Since 85

these parts are well known and form no part of the present invention, any further description would be superfluous, but if desired reference may be had to the Kennedy Patent 5 No. 1,565,244 for fuller information with respect to the keyboard connections. An assembler entrance I is arranged to receive the matrices as they are released from the magazines and carry them to the composing or assembling mechanism.

In selecting one or another of the magazines for use, the shift frame is raised and lowered within the fixed supporting frame D to bring the selected magazine into registration with the assembler entrance I at the front and the channeled conductor E at the back. Thus, in Fig. 1, the lowermost magazine is shown in operative position.

The mechanism for raising and lowering the magazine shift frame is of improved form and will now be described. Journaled in the supporting frame D centrally below the magazine shift frame is a rotary shaft O having fast thereon a single pair of cams O¹ arranged to cooperate with a similar pair of rollers O² journaled on a cross rod O³ secured at its opposite ends to the two side plates C of the magazine shift frame (see particularly Fig. 5). Surrounding the shaft O is a powerful torsion spring O⁴ fixed at one end thereto and at its opposite end to the frame D and tending to rotate the cam system to raise the magazines and thus counterbalance their weight. The shaft O is extended to the right beyond the corresponding side plate C of the magazine shift frame and is connected by a system of reducing gears, indicated generally by the reference letter O⁴, to a shaft O⁵ provided with an operating handle or hand lever J. This arrangement not only enables the operator to shift the magazines uniformly and with little effort, but the reducing gears are so proportioned as to allow the operating handle to occupy the same position after its operation irrespective of the magazine selected, which feature is of importance in effecting the proper cooperation of the handle with the locking mechanism next to be described.

60 The handle J (see Fig. 3) is provided with a spring-pressed grip M having a detent M¹ which is adapted to engage in a recess N¹ of a locking plate N² mounted in a block N fixed to the side of the supporting frame D. The block N is formed with beveled cuts N³ to engage the detent M¹ and push it outwardly as the handle is rotated, so that it may snap automatically into the recess N¹ when it comes into alignment therewith.

65 In order to insure that a selected magazine be located in proper position, I construct the locking mechanism so that the handle J cannot be engaged therewith at any other time. To this end the locking plate N² (see particularly Figs. 2 and 6) is slidably arranged

in the block N and is connected by an arm N⁴ to a rotary disk N⁵ fast to one of the gear shafts N⁶. The timing of the parts is such that when any one of the magazines is in operative position, the locking plate N² will 70 present its recess N¹ in alignment with the beveled cuts N³ (as in Fig. 2), or in position to engage the detent M¹ when the handle J has made a complete turn. On the other hand, when any one of the magazines is in inoperative position, the locking plate N² will 75 present its recess N¹ out of alignment with the beveled cuts N³ (as in Fig. 6), or out of position to engage the detent M¹ when the handle J has made a complete turn. In this connection it may be noted that two complete rotations of the handle J are required 80 to effect a change from one magazine to the next one, so that unless the operator completes both these rotations the locking plate 85 N² will remain in inactive position and the handle cannot be engaged in the recess N¹.

In many respects the improvements above described are the same as those presented in the Kennedy Patent No. 1,212,500, but they 90 differ therefrom in important particulars and as brought out more in detail in the appended claims.

Improved means for guiding the magazine shift frame as it is raised and lowered within the fixed supporting frame D are also provided as follows. At the front, the side plates C are formed with a pair of long parallel tracks C¹, and at the rear with a similar pair of shorter parallel tracks C², as well as 100 at their lower ends near the center with a third pair of tracks C³. The front tracks C¹ make running contact with two pairs of rollers d¹ journaled in massive brackets D² rising from the supporting frame D at its opposite edges, and the rear tracks C² make running contact with a single pair of rollers d² also journaled in the brackets D³. The third pair of tracks C³ make sliding contact 105 with a pair of guide members d³ (see Fig. 2) carried by the supporting frame D at its opposite edges. The tracks C³ and guide members d³ might be dispensed with if desired, but they serve the useful purpose of preventing the shift frame from turning or twisting 110 about a transverse axis in the event that undue resistance is offered to the up and down movements of the magazine shift frame. Each of the brackets D³ is provided on its inner face with a pair of adjusting screws D⁴ bearing against the outer faces of the side plates C, and serving to locate the shift frame in proper lateral position. In this connection it may be stated that the rollers d¹ and d² are mounted in eccentric bearings so that 115 they may be adjusted relatively to one another to locate the shift frame in its proper longitudinal or fore-and-aft position.

As a further improvement in the magazine mounting, and as well shown in Fig. 7, the 120

uppermost base frame B is provided at its opposite edges and near its lower end with a pair of upstanding beveled guided members K which serve to center the magazine thereon 5 when it is placed on the base frame in the act of interchanging magazines. The centering of the two lower magazines upon their respective base frames is effected by similar guide pieces K¹ (which may or may not be beveled at their forward ends) attached to the inner faces of the side plate C of the magazine shift frame.

The two upper magazines may be removed with little or no difficulty. Thus, in the case 15 of the top magazine, it need merely be lifted sufficiently at its lower end to enable the cross bar A¹ to clear the retaining lips or shoulders B¹ on the base frame. The same is true of the second magazine, except that before it can be removed the shift frame must be raised sufficiently to locate the magazine above the level of the assembler entrance I, as for example in Fig. 1. The range of action of the magazine shift mechanism however is insufficient to locate the lowermost or bottom magazine above the level of the assembler entrance, and hence it is proposed (as in the Kennedy Patent No. 1,164,359) to swing the entire magazine structure upwardly from its 25 normal position in the machine frame. This is the reason (altho not the only reason) for mounting the shift frame in the special supporting frame D, which because of its pivotal mounting in the machine frame can be swung upwardly about its pivotal point D¹ before mentioned. In the present instance, such swinging movement of the supporting frame is effected (Figs. 1 and 5) by means of a hand lever L fast to a short shaft L¹ journaled 30 in the machine frame and having an arm L² pivotally connected to a long link L³ depending from the shaft O in the supporting frame. The link L³ and arm L² function as a toggle which is straightened out by the depression 35 of the hand lever L and lifts the parts the required distance, all as shown by the dotted lines in Fig. 1. When depressed, the hand lever L brings up against a fixed stop L⁴ on the machine frame and holds the toggle in its 40 extended position, but if desired the hand lever may be locked in its depressed position by a detent L⁵ carried thereby and arranged to engage in a hole or recess L⁶ formed in a lug L⁷ depending from the machine frame.

45 Before swinging the supporting frame D upwardly in the manner just described, the magazine shift frame should be elevated to its full extent by the operation of the handle J so as to locate the lowermost magazine (the one to be removed) in operative relation to the assembler entrance I; otherwise a greater swinging movement of the supporting frame would be necessary. To insure that this is done, locking means are provided for preventing the operation of the hand lever L except 50 when the lowermost magazine is in operative position. In the embodiment illustrated, such locking means consists of a fore-and-aft latch member P pivoted centrally as at P¹ to the machine frame (see particularly Figs. 1 and 5). At its rear end, the latch member is formed with a hook P² which engages behind the hand lever L when in its elevated position; and at its forward end the latch member is formed with a beveled or cam surface P³ arranged in position to be engaged by a screw P⁴ mounted transversely in an arm P⁵ attached to the rotary cam shaft O. A spring P⁶, pulling on the rear end of the latch member, serves normally to hold it in locking position. According to this simple arrangement, when the shaft O is rotated to bring either of the two upper magazines in operative position, the screw P fails (because of the insufficient rotation of the shaft) to engage the latch member P and hence any attempt to swing the supporting frame D upwardly will be frustrated by the latch member. When however the shaft O is rotated to its full extent to locate the lowermost magazine in operative position, the screw P will engage the beveled end P³ of the latch member and, by rocking it about its central pivot P¹, will move the hook P² clear of the hand lever L. Under such conditions (the parts being in their proper position), the hand lever L may be depressed to rock the supporting frame D upwardly about its pivot D¹ and thus locate the lowermost magazine above the assembler entrance I in position for removal. While the locking latch P, in the present embodiment, subserves a special function, the invention in a broader sense contemplates any means for preventing the swinging movement of the supporting frame except when the magazines occupy a given shifted position therein, or stated differently, any means for permitting or preventing such movement of the supporting frame according to the shifted position of the magazines.

Having thus described my invention, what I claim is:

1. In a typographical machine, the combination of a plurality of magazines, and a supporting frame therefor movably mounted in the machine frame, said magazines being shiftable relatively to the supporting frame to bring one or another thereof into operative position, with means for moving the supporting frame from its normal position to facilitate the removal of the magazines, together with means for preventing such movement of the supporting frame except when the magazines occupy a given shifted position therein.
2. In a typographical machine, the combination of a plurality of magazines, and a supporting frame therefor movably mounted in the machine frame, said magazines being shiftable relatively to the supporting frame

- to bring one or another thereof into operative position, with means for moving the supporting frame from its normal position to facilitate the removal of the magazines, together with means for permitting or preventing such movement of the supporting frame according to the shifted position of the magazines.
3. In a typographical machine, the combination of a plurality of magazines, and a supporting frame therefor movably mounted in the machine frame, means carried by the supporting frame for shifting the magazines relatively thereto to bring one or another into operative position, with means for moving the supporting frame from its normal position to facilitate the removal of the magazines, together with means for preventing such movement of the supporting frame except when the magazines occupy a given shifted position therein.
4. In a typographical machine, the combination of a plurality of magazines, and a supporting frame therefor movably mounted in the machine frame, means carried by the supporting frame for shifting the magazines relatively thereto to bring one or another into operative position, with means for moving the supporting frame from its normal position to facilitate the removal of the magazines, together with means for permitting or preventing such movement of the supporting frame according to the shifted position of the magazines.
5. In a typographical machine, the combination of a plurality of magazines, and a supporting frame therefor movably mounted in the machine frame, means carried by the supporting frame for shifting the magazines relatively thereto to bring one or another into operative position, with means for moving the supporting frame from its normal position to facilitate the removal of the magazines, the said means comprising a hand lever mounted in the machine frame and connections therefrom to the supporting frame, together with means for locking the hand lever against operation except when the magazines occupy a given shifted position with reference to the supporting frame.
6. In a typographical machine, the combination of a plurality of magazines, and a supporting frame therefor movably mounted in the machine frame, means carried by the supporting frame for shifting the magazines relatively thereto to bring one or another into operative position, with means for moving the supporting frame from its normal position to facilitate the removal of the magazines, the said means comprising a hand lever mounted in the machine frame and connections therefrom to the supporting frame, together with locking means for permitting or preventing the operation of the hand lever according to the shifted position of the magazines.
7. In a typographical machine, the combination of a plurality of magazines, and a supporting frame therefor movably mounted in the machine frame, means carried by the supporting frame for shifting the magazines relatively thereto to bring one or another into operative position, with means for moving the supporting frame from its normal position to facilitate the removal of the magazines, the said means comprising a hand lever mounted in the machine frame and connections therefrom to the supporting frame, together with a locking latch cooperating with the hand lever, and means operated by the magazine shifting means for moving the latch to active or inactive position.
8. In a typographical machine, the combination of assembling devices, a plurality of superposed magazines, and means for raising and lowering the magazines to bring one or another into operative relation to the assembling devices, with further means for lifting the magazines as a whole above the level of the assembling devices, together with means for preventing such lifting of the magazines except when the lowermost magazine is in operative relation to the assembling devices.
9. In a typographical machine, the combination of assembling devices, a plurality of superposed magazines, and means for raising and lowering the magazines to bring one or another into operative relation to the assembling devices, with further means for lifting the magazines as a whole above the level of the assembling devices, together with locking means for preventing such lifting of the magazines, and means for rendering said locking means inactive when the lowermost magazine is brought into operative relation to the assembling devices.
10. In a typographical machine, the combination of assembling devices, a plurality of superposed magazines, and means for raising and lowering the magazines to bring one or another into operative relation to the assembling devices, with further means for lifting the magazines as a whole above the level of the assembling devices, the said means comprising a hand lever mounted in the machine frame and connections therefrom to the magazines, together with a locking latch to hold the hand lever against operation, and means actuated by the magazine raising and lowering means for moving the latch to inactive position when the lowermost magazine is brought into operative relation to the assembling devices.
11. In a typographical machine, the combination of a plurality of superposed inclined magazines, a shift frame in which the magazines are removably mounted, means for raising and lowering the shift frame, and means for guiding the shift frame in its up and down position.

down movements, said guiding means comprising two pairs of parallel tracks formed on the shift frame, one pair at the front and one pair at the rear, and a further pair of parallel tracks formed on the shift frame at the bottom and intermediate the front and rear tracks, stationarily mounted rollers arranged in running contact with the front and rear frame tracks, and a stationary guide arranged in sliding contact with the intermediate frame tracks.

12. In a typographical machine, the combination of magazine shifting means, an operating handle therefor provided with a spring actuated detent, a locking plate having a recess wherein the detent is adapted to engage, and means for moving the locking plate into and out of engaging relation to the spring actuated detent, said means comprising a rotary member operated by the magazine shifting means and connections therefrom to the locking plate.

13. In a typographical machine, the combination of a plurality of magazines, a pair of rotary cams for shifting the magazines to bring one or another into operative position, a transverse rock shaft upon which the cams are mounted, an operating handle mounted independently of the rock shaft, gearing connecting the handle with the rock shaft, said gearing being so proportioned that the operating handle will occupy the same position after each of its operations, a locking plate to engage and hold the operating handle in its operated position, and a rotary member operated by the gearing for moving the locking plate to and from its active position.

14. In a typographical machine, the combination of a plurality of magazines, means for shifting the magazines to bring one or another into operative position and including an operating handle, a locking plate to hold the handle in its operated position, and means operated directly by the magazine shifting means for moving the locking plate to and from its active position.

15. In a typographical machine, the combination of a magazine, a base frame whereon the magazine is removably mounted, means for supporting the magazine on the base frame, and a pair of beveled guides fixed to the frame base frame at its opposite edges and serving to center the magazine on the base frame as it is placed thereon, said guides being distinct from the magazine supporting means.

16. In a typographical machine, the combination of a plurality of magazines, a rigid shift frame comprising a corresponding plurality of base frames upon which the magazines are removably mounted, means for supporting the magazine on the base frame, and fixed abutments located on the opposite side members of the shift frame in position to

engage the opposite edges of the individual magazines to locate them in their proper central position within the shift frame, said guides being distinct from the magazine supporting means.

17. In a typographical machine, the combination of a plurality of short magazines, a channeled conductor leading thereto from the distributing mechanism, a shift frame wherein the magazines are mounted, a relatively fixed supporting frame upon which the channeled conductor is located, and means mounted in the supporting frame and connected to the shift frame for raising and lowering the same, said supporting frame being pivoted at its upper end, whereby the entire magazine structure may be swung upwardly to facilitate the removal of the lowermost magazine.

In testimony whereof, this specification has been duly signed by:

HAROLD A. BURT.
